UNITED STATES PATENT OFFICE.

ROBERT R. THOMPSON, DECEASED, BY MARY W. THOMPSON, EXECUTRIX, OF LOS ANGELES, CALIFORNIA.

DESIGN FOR A SIGNAL.

58,841.

Specification for Design. Patented Aug. 30, 1921.

Application filed May 3, 1920. Serial No. 378,704. Term of patent 14 years.

To all whom it may concern:

Be it known that I, MARY W. THOMPSON, a citizen of the United States, and a resident of Los Angeles, in the county of Los Angeles, State of California, am the executrix of the last will and testament of ROBERT R. THOMPSON, deceased, who did invent a new, original, and ornamental Design for Signals, of which the following is a specification, reference being had to the accompanying drawings, forming part thereof.

Figure 1 is a perspective view, and Fig. 2 is a side elevation, of a signal, showing the new design.

I claim:

The ornamental design for a signal, as shown.

MARY W. THOMPSON,
Executrix of Robert R. Thompson, Deceased.

Witnesses:

MARIE PORTER,
VIRGINIA BERNINGER.
